UNITED STATES PATENT OFFICE

CHARLES P. WIDDICOMBE, OF CHICAGO, ILLINOIS

LOCOMOTIVE GREASE CELLAR

Application filed March 24, 1928. Serial No. 264,429.

My invention relates to improvements in locomotive grease cellars, and has for its primary object a grease cellar in which the end wall is readily removable but is so retained in position that it can not tip outwardly permitting road dust and grit to enter a cellar and intermingle with the grease and thereby cut and score the bearings and locomotive axles.

10 In the drawings:

Fig. 1 is an end view of my cellar viewing it from the gate end;

Fig. 2 is a side view of the same;

Fig. 3 is a view similar to Fig. 1 with the 15 end gate removed;

Fig. 4 is a top plan view of Fig. 3;

Fig. 5 is a vertical section taken on the line 5—5 of Fig. 1;

Fig. 6 is a face view of the end gate employed; and

Fig. 7 is a top plan view of the same.

In the construction of my device I employ a grease cellar having a body portion which is provided with side walls 8, a bottom 9, and 25 one end wall 10. The end wall is cut away arcuately as indicated by the numeral 11 in Fig. 3 so that the cellar can be raised upwardly beneath the axle of locomotive drive wheels.

30 The forward end 12 of the cellar is left upon and is designed to be closed by means of the end gate as will be hereinafter described.

The cellar is provided with depending lugs 35 or ears 13^a which are located at the four corners and below the bottom, and are for the purpose of mounting and securing the cellar in position. The bottom 9 is provided with a depression or recess 14 which receives 40 a spring tending to press a reticulated plate upward against the lower part of the axle. This spring and plate are not shown in the drawings as they form no part of my invention and are at present in common use in grease cellars.

The edges of the walls 8 adjacent the open portion are cut away as indicated by the 45 numeral 13 so as to leave a shoulder. In other words this cut away portion is slightly wider than the interior of the cellar. The walls 8

are also provided at the open end with outwardly projecting lugs 14^a. These lugs are cut away adjacent the cut away portion 13 as indicated by the numeral 15 so as to leave a slide substantially L-shaped in cross section 55 for the edges 16 of the end gate 17. The end gate is also provided with an arcuate cut-away portions in its upper edge as indicated by the numeral 18, which serves the same purpose as the cutaway portion 11.

60 The end gate is provided with outwardly extended lugs 19 which have openings 20. These openings 20 are designed to register with openings 21 formed in the lugs or projections 14^a so as to permit the passage of a cotter key 22 and when this cotter key is in place and its end spread, all up and down movement of the end gate is prevented, while the recess portions 15 and 13 prevent any outward movement of the end gate even if the 70 cotter key 22 is not in position.

The end gate 17 is also provided with rearwardly extending lugs 23 which fit inside of the lugs 13^a at the open end of the cellar.

75 The ears or lugs 13^a, as well as the ears or lugs 23, are provided with openings 24, which receive cotter keys or bolts for securing the cellar in position beneath the axle. This peculiar type of mounting has not been shown as it is in common practice today and 80 forms no essential part of my invention.

85 The end gate 17 is placed in position by pushing it upward from the bottom of the cellar and then inserting the cotter keys 22 and also the cotter keys or bolts, which hold the open or forward end of the cellar in the bearing frame.

90 By my construction even should lugs or ears 23 become broken off, still the end gate will be held in position by means of the cotter key 22 and prevent it from dropping down while if the lugs or projections 19 should become broken off, the cotter key 22 will prevent any forward tipping of the end gate as will the slot formed between the 95 lugs 14^a and end of the cellar. In other words I have a double protection against the forward tilting of the end gate but at the same time it can be readily removed for repacking the cellar with grease. 100

The grease used for this lubrication is what is known as "hard grease" and is forced into the cellar under pressure and the heat generated by the rotation of the axle softens up a portion of this grease, which rises upward due to its expansion while being softened and furnishes the axle with sufficient lubrication.

It will also be noted that the rearwardly extending lugs 23 limit the upward movement of the end gate so that the movement of the gate is limited both upward, forward and back and downward, the forward and back movement being prevented by the lugs 14^a which overlap the vertical edges of the end gate and the downward movement by means of the cotter key 22 as well as by the means which pass through the lugs 23 and 13^a when the cellar is secured beneath the axle.

Having fully described my invention, what I claim is:—

1. A grease cellar comprising a body portion completely open at its top and one end, a vertically slidable gate carried by said body portion for closing said open end, and perforated lugs carried by the body portion and gate, said lugs adapted to receive a fastening means for preventing movement of said gate.
2. A grease cellar comprising a rectangular container entirely open at its top and one end, a removable end gate for closing said open end, lugs substantially L shaped in cross section integral with the side walls of the container and overlying a portion of the vertical edges of said end gate whereby said gate is vertically slidable, perforated lugs projecting at right angles from said end gate parallel to and adjacent the first mentioned lugs, and a fastening means extending through the perforations of said first and second mentioned lugs for preventing vertical movement of said end gate.
3. A grease cellar comprising a rectangular container entirely open at its top and at one end, a vertical slidable end gate for closing the open end of said container, means carried by the lower end of said gate for limiting its upward movement, means substantially L shaped in cross section carried by said container for preventing outward tilting of said gate, and means for holding said gate against accidental downward movement.

In testimony whereof I have affixed my signature.

CHARLES P. WIDDICOMBE.
